UNITED STATES PATENT OFFICE.

HEINRICH BOCKISCH, OF POUGHKEEPSIE, NEW YORK, ASSIGNOR, BY MESNE ASSIGNMENTS, TO WELTE-MIGNON CORPORATION, OF NEW YORK, N. Y., A CORPORATION OF NEW YORK.

AUTOMATIC MUSICAL INSTRUMENT.

Application filed November 20, 1919. Serial No. 339,260.

To all whom it may concern:

Be it known that I, HEINRICH BOCKISCH, a citizen of Czecho-Slovakia, residing at Poughkeepsie, in the county of Dutchess 5 and State of New York, have invented certain new and useful Improvements in Automatic Musical Instruments, of which the following is a specification.

The automatic mechanism forming the essence of the present invention may be very usefully employed or embodied in, or in connection with, an organ, orchestrion or other like instrument having a series of tone-emitting elements for manual scales and a series 15 of tone emitting elements for pedal scales, its employment in such case being as a means for selectively operating the tone-emitting elements so that the tones emitted will be manual tones alone, pedal tones 20 alone, or both manual and pedal tones together, in any of the infinite variety of combinations of manual and pedal tones necessary to the proper rendition of musical compositions.

25 In organ compositions, the manual scales and the pedal scale should be operable independently of each other. This permits, for example, the playing of a chord on a very soft stop—as violin—on the first manual, 30 while at the same time a solo in a different tone color—as oboe—is being played on the second manual and a very deep soft note on a 16 foot bourdon is being sounded in the pedal.

35 In pipe organs and other musical instruments of analogous nature whose tone-emitting elements are formed to give forth musical tones when subjected to the influence of currents of air and in which there is generally a very extensive scale, running from 40 very low notes in the pedal to high notes in a manual, or in a plurality of manuals, the provision of each manual and pedal scale with a separate series of tone ducts, in order 45 that the playing of the same may be controlled by a perforated note sheet, or other appropriate “record”, would necessitate a great number of such ducts and the record for opening and closing the ducts would 50 have to be correspondingly wide, if it be a perforated note sheet, or long, if it be a cylinder with projections, for example. The objections to the use of records of such character are apparent.

55 Having all the foregoing in mind I in-

vented and have patented three generically similar but particularly different embodiments of mechanism having the foregoing functions and advantages. These patents were all issued September 5, 1916, and are 60 numbered 1,197,573; 1,197,574 and 1,197,575, respectively. They were issued to M. Welte & Sons, of New York, N. Y., a corporation of New York, assignee, to whom this invention 65 belongs.

This application relates to a further particular embodiment of the same generic invention having the same purposes in view and an additional purpose, to wit, to simplify the construction and render the parts 70 more accessible for inspection and repair.

This stated purpose or object and others which will be apparent to those familiar with these inventions and the art to which they have reference are secured by the construction illustrated in the accompanying drawings, wherein:

Fig. 1 is a diagrammatic sectional view of mechanism embodying the present improvements;

Fig. 2 is a perspective view, partly in section, on a larger scale than Fig. 1, of the particular parts of the mechanism for controlling pedal effects which differ in detail from my former inventions hereinbefore 85 named.

Figs. 3, 4 and 5 are detail representations of the perforated note sheet which I prefer to employ as the record for operating the mechanism, this note sheet being the same 90 as that shown in my former patents.

Similar characters of reference denote corresponding parts in the several views.

A and B designate portions of the organ wind chest for manual notes and pedal notes 95 respectively. These are provided with chambers marked A' and B', respectively, to which the tone-emitting elements C and C', as organ pipes, for example, are connected. There are a series of tone-emitting 100 elements connected with each chamber A' and B', each element giving forth a different note and each series forming a scale or set. When, as in an organ, orchestrion or the like, it is desired to embody in the instrument a plurality or series of tone-emitting elements giving forth different qualities of tone of the same note, it is preferred, as is usual in organs, to provide each portion 105 A and B of the wind chest with a plurality 110

of chambers A', B', corresponding in number with the number of the qualities of tones which are to be produced. To exemplify this, the portion A of the wind chest appropriated to the manual notes or effects is shown as having a plurality of chambers A' each of which, in practice, has connection with a series of tone-emitting elements C which form parts of the manual scales and are preferably so arranged that those elements which emit different qualities of tone of the same note will be in line with each other but connected to the different chambers, as shown. Similarly, the portion B of the wind chest appropriated to the pedal notes or effects is, for the sake of example, illustrated as having two chambers B' provided with two lines of tone-emitting elements C' of different qualities of tone, forming parts of the pedal scale. The same lineal arrangement of the elements giving forth different qualities of tones of the same note explained with reference to the portion A, is illustrated with respect to the portion B. The connection between each chamber and the tone-emitting elements controlled therefrom includes a valve c. These valves open and close passages c' between the chambers and the respective tone-emitting elements. The valves forming a set, for the elements emitting different qualities of tones of the same note are connected with each other preferably by rods c², each having a spring, c³, for closing the valves connected thereby. The chambers A' and B' are connected with a suitable source of supply of air under pressure and have valves A², B², suitably operated to admit the air to the respective chambers. In the ordinary humanly played organ these valves B² are connected with the stops of the organ. In the present instance they are operated automatically, preferably by the means illustrated and described in my Patent Number 1,197,573, hereinbefore named.

D designates a tracker board containing the mouths of a series of tone ducts 12 and the mouths of a pair of control ducts 1 and 2. Certain of the tone ducts 12 are common to the valves c of the manual and pedal chests. For example, if the manual has a scale of sixty-one (61) notes and the pedal has a scale of thirty (30) notes additional to those of the manual, the ducts 12 for the lowest thirty notes of the manual scale are employed for the pedal scale also, the remaining thirty-one (31) notes of the manual scale having a separate duct for each such note. This invention is concerned only with the scales having ducts 12 common to both.

The mechanism connecting the ducts 12 respectively with the corresponding sets of valves c includes primary operating pneumatic elements E and G and secondary op-

erating pneumatic elements F and H. The connections between the primary operating pneumatic elements E and the secondary operating pneumatic elements F include a parallel electric circuit, hereinafter described, forming parts of "manual tone circuits," circuit making and breaking elements, as the circuit closing elements e, g, controlled by the elements E and G and means, as magnets f, respectively operated by said circuits and controlling through intermediate mechanism mounted in a secondary manual tone chest I, the relative pressures which operate the elements F.

Similarly, the connection between the primary operating pneumatic elements G and secondary operating pneumatic elements H include parallel electric circuits hereinafter described, forming parts of "pedal tone circuits," circuit making and breaking elements, as the circuit closing element g, controlled by the elements G, and means, as magnets h, respectively, operated by said circuits and controlling, through intermediate mechanism, hereinafter described, in a secondary pedal tone chest I', the relative pressures which operate the pneumatics H.

The mechanism in the chests I and I' may be substantially the same as that previously employed by me for a similar purpose and disclosed in my patents hereinbefore named. Only one section of each is shown. They are hereinafter particularly described. The pneumatic elements F and H thereof are connected with the respective valve rods c² preferably by means, F' and H', similar to that heretofore employed by me.

The control ducts 1 and 2 are connected with chambers 3 and 3^a in primary control members J and J', respectively having primary control valves 4 and 4^a arranged in chambers 5 and 5^a. These members J and J' also have other chambers 6 and 6^a, respectively, separated from the chambers 3 and 3^a by membranes 7 and 7^a to which the stems 8 and 8^a of the primary control valves 4 and 4^a are connected. The valve 4 opens and closes ports 9 and 10 alternately, and through these ports respectively the chamber 5 has communication with the atmosphere or with the chamber 6, and the valve 4^a alternately opens and closes ports 9^a and 10^a through which the chamber 5^a similarly has communication with the atmosphere or with the chamber 6^a. The chambers 6 and 6^a are under suction and are connected with the chambers 3 and 3^a respectively by bleed holes 11 and 11^a.

The tone ducts 12 are respectively connected with chambers 13 in a primary tone chest, K, which is common to both the secondary manual tone chest I and the secondary pedal tone chest I'. This chest K comprises (in addition to the chambers 13) 130

primary tone valves 14, chambers 15 in which said valves work, chambers 16 which are under suction and are separated from the chambers 13 by membranes 17 connected to 5 the stems 18 of the valves 14, atmospheric ports 19 to the chambers 15, suction ports 20 between chambers 15 and 16, and bleed holes 21 between chambers 13 and 16.

As thus far described the chests I, I' and 10 K and ducts 1, 2 and 12 are structurally and functionally similar to the corresponding parts of the patents hereinbefore named: the ducts 12 being tone ducts common to the pedal and manual scales, and the ducts 15 1 and 2 being control ducts for determining whether the tones shall speak in the pedal alone or in both pedal and manual, the mechanism being so arranged that when neither control duct is opened the manual 20 scale alone will be played, as in my patents referred to. It will be understood that the number of ducts 12 and valves 14 corresponds to the number of notes common to pedal and manual scales and that there is 25 one such duct and valve for each note, or one for each set of connected valves *c* when there are a plurality of such valves controlling the emission of tones of different qualities of the same note. It will similarly be understood that there is only one 30 duct 1 and primary valve 4 for the entire series of tones in the pedal scale, and one duct 2 and primary valve 4^a for the entire series of tones in the manual scale.

35 In this particular exemplification of the invention there is one primary operating pneumatic element E for each note of the manual scale and each has a circuit closing member *e* secured to its movable board, and 40 similarly there is one primary operating element G for each note of the pedal scale and each has a contact member secured to its movable board. Moreover, in this particular exemplification of the invention the series of 45 primary operating pneumatic elements G for the pedal scale are mounted in a suction chamber L' of a box L: and the series of primary operating pneumatic elements E for the manual scale are arranged in a 50 suction chamber M' of a box M. The box L has a channel N the air in which is normally rarefied but may be changed to atmospheric pressure: and the box M has a similar channel O, the air in which is normally at atmospheric pressure but may be changed to less 55 than atmospheric. The changes in the pressures of the air in these channels are effected automatically from the primary control members J and J' through intermediate 60 mechanisms the preferred construction of which will now be described:

The intermediate mechanism for changing the air pressure in channel N includes a secondary control valve which preferably 65 comprises a stem 25 and valve members or

heads 26 and 27 on opposite ends of the stem. The valve member 26 is mounted in a chamber 28 containing air whose pressure is less than atmospheric and opens and closes a port 29 through which said chamber has 70 communication with a duct 30 connected to the channel N. The other valve member, 27, opens and closes communication of the duct 30 with the atmosphere. The valve member 26 rests upon a membrane 31 one side of 75 which is constantly subjected to the less than atmospheric pressure in the chamber 28 and the other side of which is subjected to the pressure in a chamber 32, which is connected to chamber 28 by a bleed hole 33. 80 Chamber 32 is provided with an atmospheric duct 34 which is opened and closed by a valve 35 carried by the armature 36 of an electro-magnet 37. This magnet is in a "control circuit" controlled by the primary 85 control valve 4 as hereinafter more particularly set forth. It will be seen that when this magnet is de-energized the way between the duct 30 and the suction chamber 28 will be open and the way between said duct and the atmosphere will be closed, and hence the air in channel N will be at less than atmospheric pressure. It will be apparent that if the magnet 37 be energized, its armature 36 will thereby be attracted and atmospheric duct 34 will be opened. Air at atmospheric pressure will then enter chamber 32, thereby moving valve 26, and cutting off communication of duct 30 with suction chamber 28 and at the same time moving 90 valve member 27 and opening communication of said duct 30 with the atmosphere, thus changing the pressure of the air in channel N from less than atmospheric to atmospheric. 95

100 The intermediate mechanism for changing the air pressure in channel O includes a secondary control valve 38, mounted in a chamber 39 having an atmospheric port 40 and a suction port 41, the latter opening 110 into a suction chamber 42 which is separated from a chamber 43 by a membrane 44 connected to the stem 38^a of the valve 38. It is preferred to control the pressure of the air in the chamber 43 by what I call a sub-primary control valve which preferably 115 comprises a stem 45 having valve-members 45^a and 45^b on opposite ends thereof. This sub-primary control valve is operated by a membrane 46, located between and subjected 120 to the pressures in the suction chamber 42 and a chamber 47. The stem 45 extends through a port 48 one end of which is open to the atmosphere and the other end of which is open to the suction chamber 42, and the valve-members 45^a and 45^b are so correlated with this port that the port is open to the suction chamber and to the atmosphere alternately. This port 48 is connected with 125 chamber 43 by a channel 49, and chambers 130

43 and 47 are connected with suction chamber 42 by bleed holes 50 and 51.

Chamber 47 is provided with an atmospheric duct 52 which is opened and closed 5 by a valve 53 carried by the armature 54 of an electro-magnet 55, which is in a control circuit though opened and closed under control of the primary control valve 4^a as hereinafter explained. It will be understood 10 that when the magnet 55 is not energized, which is what I call the "normal condition" because it is the condition which most frequently exists in this exemplification of the invention, atmospheric port 40 is open 15 and channel O will be in communication with the atmosphere through duct 56, chamber 39 and port 40: and that when said magnet 55 is energized; the duct 52 will be opened to the atmosphere, thereby causing 20 valve-member 45^a to close port 48 against suction and valve member 45^b to open said port to the atmosphere, whereupon chamber 43 will be in communication with the atmosphere, through channel 49 and port 48, thus 25 causing valve 38 to be moved and to close the atmospheric port 40 and open the suction port 41, resulting in the attenuation of the air in channel O, which now is in communication with suction chamber 42, through 30 duct 56, chamber 39 and port 41. It will be observed that by reason of the provision of a sub-primary valve for controlling the secondary control valve 38, which latter should be comparatively large, the change 35 of the pressure in channel O from atmospheric to less than atmospheric is very quickly effectuated.

The magnet 37 is energized by one of the "control circuits", i. e., the one under control 40 of the primary control valve 4, to change the pressure of the air in channel N from less than atmospheric to atmospheric by the collapsing of a pneumatic, as bellows a⁶, for example, having a contact a⁵ to bridge 45 the space between contact wires a¹ and a³. The wire a¹ is connected with the positive pole of a suitable source of electric potential indicated at P by a wire a, and the wire a³ is connected with the magnet 37 by a 50 wire a², and said magnet is connected with the negative pole of the source by a wire a⁴.

The magnet 55 is energized by the other "control circuit", i. e., the one under control 55 of the primary control valve 4^a, to change the pressure of the air in channel O from atmospheric to less than atmospheric by the collapsing of a pneumatic, as bellows b⁶, for example, having a contact b⁵ to bridge 60 the space between contact wires b¹ and b³. The wire b¹ is connected with the positive pole of the source P, by wire b⁴, and the wire b³ is connected with the magnet 55 by a wire b², and said magnet is connected with the negative pole of the source by a wire b⁵.

65 Channel N, in this exemplification of the

invention, is connected through a series of ports 57 with the before mentioned series of primary operating pneumatic elements G, there being one of said ports and elements for each pedal note. These pneumatic elements are preferably bellows mounted, as stated, in the suction chamber L' of a chest L. They are provided with springs 59 for holding them normally in collapsed condition and their circuit closing devices 58 75 carry the hereinbefore mentioned electrical circuit closing elements g and each of these contacts bridges the space between a pair of contact wires c and c' to energize the corresponding magnet h. There is one of these 80 magnets for each pedal note.

Channel O in this exemplification of the invention similarly is connected, through a series of ports 60 with the hereinbefore referred to series of pneumatic elements E, 85 one for each manual tone. These elements are preferably bellows mounted, as stated, in the suction chamber M' of the chest, M. They are provided with springs 61^a for collapsing them when their internal pressure is reduced from atmospheric to less than atmospheric. Their circuit closing devices 61 carry the circuit closing elements e for bridging the spaces between pairs of contact wires d, d', respectively, to energize the 90 hereinbefore referred to magnets f of the secondary manual tone chest I.

For each primary pedal operating element G there is a locking-pneumatic 75 provided with a projection 76 movable into and out of the path of the corresponding circuit closing element g; and for each primary manual operating element E there is a locking-pneumatic 77 provided with a projection 78 movable into and out of the path of the corresponding circuit closing element e. Each pneumatic 75 is provided with a duct 79 and each pneumatic 77 is provided with a duct 80. The ducts 79 and 80 for the locking pneumatics which correspond to each other 105 are connected to a channel 81 common thereto. It will be understood that there is one channel 81 for each pair of ducts 79 and 80. These channels respectively are in communication with ports 82 which extend from a 110 suction chamber 83 to the atmosphere. The pressure of the air in the respective channels 81 is controlled by valves, hereinafter called "locking valves" each of which preferably comprises two valve members 84 and 85, 115 mounted on opposite ends of a stem 86. The valve members 84 are in the chamber 83 and the valve members 85 are in the atmosphere: hence when the ports 82 are closed to the suction chamber they will be open to the atmosphere, and vice versa. Said ports are normally closed to the atmosphere and open to suction, and hence the pneumatics 75 and 77 are normally collapsed. Air at atmospheric pressure is admitted to these pneu- 120 125 130

matics to expand them, by admitting atmospheric air to a chamber 87 which is separated from the chamber 83 by a membrane 88 which engages the valve member 84 and 5 when distended raises said valve member and also the valve member 85, thus closing the channel 81 against the suction chamber and opening it to the atmosphere. The chamber 87 is connected to chamber 83 by 10 a bleed hole 89. An atmospheric duct 90 extends to the chamber 87. It will be understood that there is one atmospheric duct 90, chamber 87, locking-valve and membrane 88 for each channel 81 and as each duct 90 15 may be opened and closed independently of every other, it follows that the channels 81 are severally controllable and hence each pair of locking pneumatics 75 and 77 may be collapsed or expanded independently of 20 every other pair of said pneumatics. The opening and closing of the ducts 90 are accomplished by energizing and deenergizing electro-magnets 91—one for each said duct—whose armatures 91^a are provided with 25 valves 92. These magnets 91 are in circuits which are opened and closed under control of the primary tone valves 14, respectively; that is to say, they are in "tone circuits". Each of these tone circuits includes contact 30 wires g' and g⁴, the space between which is bridged by a contact g² carried by a pneumatic g³, which pneumatic is preferably a bellows whose interior is in communication with the corresponding chamber 15 of the 35 primary tone chest K, so that when valve 14 is moved by the opening of the corresponding tone duct 12 and closes atmospheric port 19 and open suction port 20, the bellows g³ will be collapsed and will thereby move its 40 contact g² into bridging engagement with terminals g', g⁴.

It should be understood at this point that when the parts are arranged as herein exemplified, the closing of the control circuit through the magnet 37 is a preparatory function and that it occurs immediately prior to the closing of the tone circuits through those magnets 91 which correspond to the notes to be sounded in the pedal and manual simultaneously; and that the closing of the control circuits through the magnets 37 and 55 similarly is a preparatory function and occurs immediately before the closing of the tone circuits through the magnets 91 corresponding to the notes to be sounded, when pedal tones or effects alone are to be produced, i. e., when the manual (which is operative when both ducts 1 and 2 are closed and consequently neither magnet 37 nor magnet 55 is energized and is also operative when duct 1 is open and duct 2 closed) has been excluded by the opening of duct 2 which, as before explained, energizes magnet 55 and thereby causes the 60 air in channel O to be attenuated.

When the air in channel O is thus attenuated, the tendency, of course, is to collapse all the pneumatics E and thereby withdraw all the circuit closing elements e from engagement with contact wires d', d'. If this 70 tendency was not resisted, as to those pneumatics corresponding to tone ducts 12 which are open at the moment the control duct 2 is opened, all manual tones would cease immediately upon the opening of the control 75 duct 2. Likewise, when control duct 2 is closed and the air in channel O becomes atmospheric, the tendency of course is for all the pneumatic operating elements E to expand and carry their contacts e into engagement with contact wires d, d', and if this 80 tendency were not resisted as to those elements corresponding to tone ducts 12 which are open at the moment the tone duct 2 is closed, the tones controlled by said ducts 85 12 would sound in the manual as well as in the pedal. Similarly, the tendency is for all pneumatic operating elements G to expand and carry their circuit closing elements g into engagement with contact wires 90 c, c' whenever duct 1 is opened and to collapse and withdraw their contacts from such engagement as soon as said duct is closed; so that this tendency unless restricted as to those elements which are connected to 95 open tone ducts would introduce a pedal tone where it was not wanted or cut it off too soon. To permit the employment of a record having short control openings, to open the control ducts immediately prior 100 to the opening of those tone ducts 12 for tones which are to be affected by the control ducts and to close as soon as said ducts commence to open, and to assure the maintenance of the tones for the full time the 105 respective tone ducts are open, to thereby make it possible to render correctly any organ composition, I have arranged the sets of pairs of locking pneumatics 75 and 77 hereinbefore referred to in the tone circuits 110 so that they respectively retain the positions to which they were set by the opening of a tone duct unless said tone duct has been closed. Accordingly, the tendency of the pneumatic operating elements E to collapse whenever control duct 2 is opened, or the tendency of pneumatic operating elements G to expand whenever duct 1 is opened, is resisted as to those elements E or G corresponding to open tone ducts 12 because 115 120 when said ducts were opened the corresponding locking pneumatics 77 or 75 were expanded and their members 78 or 76 were carried into the path which would be traversed by the corresponding circuit closing elements e or g in receding from the contact wires d, d', or approaching the contact wires c, c' and thus prevent such movement and thereby maintain the circuit closing elements e in engagement with the wires 125 130

d d', and prevent engagement of the circuit closing elements *g* with the contact wires *c, c'*. Similarly, the tendency of the pneumatic operating elements *E* to expand when 5 duct 2 is closed, and the tendency of the pneumatic operating elements *G* to collapse when duct 1 is opened is resisted as to those elements *E* or *G* corresponding to open tone ducts 12 because when said ducts were 10 opened the corresponding locking pneumatics 77 and 75 were expanded and their members 78 and 76 were moved into the paths which would be traversed by the respective circuit closing elements *e* and *g* and will 15 thereby prevent such respective expansion or collapse and accordingly will prevent engagement of said circuit closing elements *e* with contact wires *d, d'*, and maintain engagement of the circuit closing elements *g* 20 with the contact wires *c, c'*. Obviously, however, all those operating elements, *E, G*, which do not correspond to open tone ducts 12 will be instantaneously moved by the opening or closing of control ducts 1, 25 2, because the locking pneumatics 75, 77, for these particular elements, *E, G*, are not at this time expanded and accordingly their members 76, 78 are not engaged with or in the paths of the circuit closing elements 30 *e, g*.

Thus it will be seen that the locking pneumatics are important as they permit the control ducts to be closed at the moment the ducts 12 corresponding to tones to be 35 affected by the control ducts are opened, so that all the control elements and all the parts except those corresponding to affected tones are ready for the next tone or tones called for by the composition. The correlation of parts is such that any pedal tone 40 may be sounded with any manual tone, or any manual tone may be sounded alone or any pedal tone may be sounded alone.

I have already traced diagrammatically 45 the circuits between the source *P* and the respective magnets 37 and 55 and will presently trace diagrammatically the circuits which are closed (1) when the manual is playing alone, (2) when pedal tones or effects 50 are introduced with corresponding manual tones, and (3) when the pedal is playing alone; but before doing this I will briefly describe the preferred construction of the chests *I, I'* previously referred to as being 55 substantially identical with corresponding parts hitherto employed by me and shown and described in my patents hereinbefore named.

Only one section of each chest is shown, 60 that is to say, the section for one secondary operating pneumatic element. It will be understood that there is a like section for each note. As the two chests are alike in construction, except that the manual chest *I* 65 may have more sections than the pedal chest

I', the same reference characters have been employed to designate corresponding elements of the two chests. Each section comprises for each manual and pedal tone, a valve chamber 63 having a suction port 64 70 and an atmospheric port 65; a chamber 66 having an atmospheric duct 67 to be opened and closed by a valve 68 carried by the armature *f'* of the corresponding magnet *f*; a membrane 69 forming one wall of the chamber 75 66; a valve 70 in the chamber 63, having its stem 70^a connected to said membrane. The several suction ports 64 of the chest *I* open into a common suction chamber 62, and the like ports 64 of the chest *I'* open into a like common suction chamber 62. Hence it will be seen that whenever a magnet 70 or *h* is energized, the corresponding valve 80 70 will be moved to close its atmospheric duct 65 and open its suction duct 64, thereby collapsing the corresponding pneumatics 85 *F* or *H*.

The operation is as follows:

Whenever a tone duct 12 is opened the corresponding pneumatic *g*³ of the primary 90 tone chest *K* is collapsed, thereby causing the contact *g*² to bridge the space between contact wires *g*¹ and *g*² and closing an electric circuit through which the corresponding magnet 91 is energized, this circuit being as 95 follows: from the positive pole of the source *P*, by wire *x* to bus bar *X*; from the terminal *x'* on said bar corresponding to the duct which has been opened, by wire *g*³ to the corresponding magnet 91; through said 100 magnet and from its terminal *g*⁶ by wire *g*⁵ to contact wire *g*⁴; and through bridge contact *g*², contact wire *g*¹ and wire *g* to the negative pole of the source. The energizing 105 of each magnet 91, causes the corresponding pair of locking-pneumatics 75 and 77 to be inflated.

If neither of the control ducts is opened at this time, the tone will be sounded in the manual alone, it being remembered that the 110 primary operating pneumatic element *E* is normally inflated and the circuit closing elements *e* operated thereby accordingly, normally bridge the spaces between the pairs of contact wires *d, d'*, respectively. The 115 several wires *d* are connected by wires *x*³ to the respective terminals *g*⁶, and the several wires *d'* are connected by wires *x*⁴ to the respective magnets *f*. The negative sides of said magnets *f* are respectively connected 120 by wires *x*² with terminals *x'* on the bus bar *X*. Hence the magnets *f* are in parallel, circuits (forming parts of the manual tone circuits) extending from the terminals *g*⁶ to the terminals *x'* and which circuits include 125 the contact wires *d* and *d'* and circuit closing elements *e*.

When any pedal tone is to be introduced with a corresponding manual tone, the control duct 1 is opened slightly in advance of 130

the opening of the particular tone duct 12 corresponding to the note to be influenced. This, as already stated, is a preparatory function and causes the pneumatic a^6 of the 5 primary control member J to collapse and its contact a^5 to bridge the gap between contact wires a' and a^3 , thus closing the control circuit to magnet 37 and changing the pressure of the air in channel N from less 10 than atmospheric to atmospheric. All the primary operating pneumatic elements G, except those corresponding to open tone ducts 12, are instantaneously inflated and their circuit closing elements g are thus 15 moved to bridge the gaps between the respective pairs of contact wires c and c', and accordingly is a preparatory function. The respective organ magnets h of the pedal are in parallel circuits (forming parts of the 20 pedal tone circuits;) comprising wires g^{10} extending from the respective terminals g^6 to the contact wires c', wires g^{11} extending from the contact wires c to the respective magnets h and wires g^{12} extending from the 25 respective magnets to the corresponding terminals a' on the bus bar X. Hence, the several magnets h are in parallel circuits extending from the terminals g^6 to the terminals a' and which circuits include the 30 contact wires c and c' and circuit closing elements g. It will be noted that while at this moment all the circuit closing elements g (except those connected to tone ducts already open) are bridging the spaces between 35 the pairs of contact wires c c' yet the tone circuit corresponding to the note to be played in the manual and pedal is interrupted at the primary tone chest K until the tone duct 12 corresponding to said note has been 40 opened. When a duct 12 has been opened the tone circuits which include the corresponding magnets 91, h and f are all closed, as will be apparent.

It will be noted that when said tone duct 45 12 was opened and the corresponding magnet 91 thereby energized, air at atmospheric pressure was introduced into the corresponding pair of locking-pneumatics 75 and 77, thus inflating them and holding them in inflated condition until the tone duct is closed. The inflation of pneumatic 75 moves its element 76 back of the corresponding circuit closing elements g of the inflated pneumatic element G, and hence acts as a stop against 50 said contact for holding it into bridging engagement with the contact wires c, c', assuring that this contact is maintained in such engagement for the full length of time that the tone duct is opened. The remainder of 55 the elements G, not thus held, are allowed to collapse. Similarly, the inflation of locking-pneumatic 77 moves its element 78 back of the corresponding circuit closing elements e, and holds said contact firmly against the 60 corresponding pair of contact wires d, d' as

long as the corresponding tone duct is open, thereby assuring that there shall be no interruption in the manual tone whose duct 12 is open, due to the opening of a control duct 2, preparatory to playing a succeeding note in 70 the pedal alone.

When a note is to be sounded in the pedal alone both ducts 1 and 2 are opened. The opening of duct 1, as already set forth, results in the expansion of all the unrestrained pneumatics G and the moving of their contacts into bridging engagement with the terminals c, c' so that the circuit through any one or more of the magnets h will be closed when the corresponding tone ducts 12 are 80 opened. The opening of duct 2, on the other hand energizes the magnet 55 by collapsing the pneumatic b^6 of member J'. The energizing of magnet 55, as already explained, opens the duct 56 to suction and closes it 85 against air at atmospheric pressure. All the unrestrained pneumatic elements E are thus collapsed, thereby moving their circuit closing elements e out of bridging engagement 90 with terminals c, c' and breaking the circuits to the magnets f. The opening now of a tone duct or ducts 12, obviously will result in the sounding of the note or notes in the pedal only. It will be understood from the foregoing explanation, that when a tone duct 95 is now opened, the corresponding magnet 91 will be energized thus inflating the corresponding locking pneumatics 75 and 77, the pneumatic 75 moving its element 76 behind the corresponding circuit closing element g 100 into locking relation therewith, and the pneumatic 77 moving its element 78 between the corresponding circuit closing element e and the pairs of terminals d, d' to be bridged thereby and preventing inflation of the pneumatic element E connected to said circuit closing element until the tone duct the opening of which inflated the pneumatic 77 has 105 been closed, whereupon both of said pneumatics will be deflated by the de-energizing 110 of the corresponding magnet 91, resulting in the closing of the ducts 79 and 80 against the atmosphere and the opening of said ducts to the suction in the chamber 83.

Stops 100 and 101 for each locking pneumatic 115 75 and 77 are preferably provided to regulate the extent of movement of said pneumatics, and to provide for adjustment, the stops 100 are preferably composed of threaded stems having apertured heads for 120 convenience in turning them. Stops 102 are also preferably provided to limit the extent of expansive movement of the pneumatics E and G.

Thus it will be seen that I have provided 125 a simple and very practicable mechanism by which any one or more tones in the pedal scale or any one or more tones in the manual scale may be sounded alone, or any one or more tones in either scale may be sounded in 130

combination with any one or more tones of the other scale, from a series of tone ducts common to both scales. A simple and practicable means by which the control ducts 5 may be opened and closed in proper relation to the tone ducts, to produce the effects stated, is the perforated note sheet N illustrated in Figs. 3, 4 and 5 and which note sheet, being identical with that already employed by me for the same purpose and shown and described in my patents hereinbefore named, need not be particularly described herein. It will be seen that n are the 10 tone apertures in the note sheet, n' the special aperture which registers with the mouth of the control duct 1 and n^2 the special aperture which registers with the mouth of the control duct 2: and it will be noted that the rear ends of the special apertures n' and 15 n^2 are in line transversely of the sheet with the forward ends of the tone apertures n which they are to influence. They do not, in this exemplification, influence notes controlled by tone apertures which are otherwise related to the special apertures than as 20 just described.

While I have illustrated and described somewhat minutely a particular detail embodiment of the invention I nevertheless 30 would have it understood that this is merely a preferred detail embodiment and that changes in the details may be made without departing from the spirit of the invention or the substance of the appended claims. 35 Hence the invention is not restricted to the particular details of construction herein illustrated to exemplify a desirable embodiment. I particularly call attention to the fact that in an application filed of even 40 date herewith I have exemplified an embodiment of the invention which is generically similar in many respects, but specifically different from this embodiment. The generic features common to the two embodiments 45 are claimed herein. Moreover, while I have shown only one manual scale it is apparent that more than one such scale may be included and that this will require substantially a duplication only of the mechanism 50 herein set forth for the one manual scale, including the addition of a control duct, a control valve, and a switching mechanism and their associated parts for each additional scale. The operating characteristics 55 of such additional manual or manuals will preferably be similar to those described with relation to the pedal, that is to say, the pneumatics of the additional manuals corresponding to the pneumatics E will prefer- 60 ably be deflated when the corresponding tone ducts are closed.

With the detail construction described, the tracker board A , control members B and B' and primary tone chest C may be 65 in a console arranged at a distance from

the organ proper and the rest of the mechanism may be in said organ proper.

Having thus described the invention what I believe to be new and desire to secure by Letters Patent, is:—

1. In a record controlled musical instrument, a plurality of scales of tone-emitting elements; a series of tone ducts common to said plurality of scales and mechanism to establish an operative relationship between 75 any one or more of the tone-emitting elements of either scale alone, or any one or more corresponding or non-corresponding elements of both scales together, and their tone-ducts, the said mechanism including 80 control ducts and movable members operated under control of the control ducts to establish or break the connections to the tone-emitting elements, and also including locking elements and means under control of 85 the tone-ducts, for moving the locking elements into holding relation with the movable members.

2. In a record controlled musical instrument, a plurality of scales of tone-emitting 90 elements; a series of tone ducts common to said plurality of scales and mechanism to establish an operative relationship between any one or more of the tone-emitting elements of either scale alone, or any one or 95 more corresponding or non-corresponding elements of both scales together, and their tone-ducts, the said mechanism including control ducts, tone circuits having movable circuit making or breaking members under 100 control of the control ducts, locking elements and means under control of the tone-ducts for maintaining the locking elements in holding relation with the respective circuit making and breaking members.

3. In a record controlled musical instrument, a plurality of scales of tone-emitting elements; a series of tone ducts common to said plurality of scales and mechanism to establish an operative relationship between 110 any one or more of the tone-emitting elements of either scale alone, or any one or more corresponding or non-corresponding elements of both scales together, and their tone-ducts, the said mechanism including 115 control ducts, tone circuits having a set of circuit making or breaking members for each scale of tone-emitting elements and an additional set of circuit making or breaking members common to both scales, means for operating the additional set of circuit making or breaking members under control of the tone-ducts, respectively, means for operating the first-mentioned sets of circuit making or breaking members under control 120 of the control ducts, respectively, a set of locking elements for each first-mentioned set of circuit making or breaking members, and means under control of the tone ducts for operating the locking elements.

4. In a record controlled musical instrument, the combination with a plurality of scales of tone-emitting elements, a series of tone ducts common to said plurality of scales and mechanism to establish an operative relationship between any one or more of the tone-emitting elements of either scale alone, or any one or more corresponding or non-corresponding elements of both scales together, and their tone ducts, the said mechanism including control ducts, operating pneumatics, means under control of the control ducts for controlling the relative pressures to which the operating pneumatics are subjected, connections between the operating pneumatics and the tone-emitting elements, including movable members operated by said pneumatics to make or break the connections, locking elements and means under control of the tone ducts for moving the locking elements into holding relation with the movable members.

5. In a record controlled musical instrument, the combination with a plurality of scales of tone-emitting elements, a series of tone ducts common to said plurality of scales and mechanism to establish an operative relationship between any one or more of the tone-emitting elements of either scale alone, or any one or more corresponding or non-corresponding elements of both scales together, and their tone ducts, the said mechanism including control ducts, operating pneumatics, means under control of the control ducts for controlling the relative pressures to which the operating pneumatics are subjected, connections between the operating pneumatics and the tone-emitting elements, including movable members operated by said pneumatics to make or break the connections, locking elements, pneumatics connected to said locking elements respectively, and means under control of the tone-ducts for controlling the relative pressures to which the last named pneumatics are subjected.

6. In a mechanism of the class described, the combination with the two separate scales of tone-emitting elements, a series of tone ducts common thereto and control ducts for the scales, respectively, of operative connections between the ducts and tone-emitting elements, said connections including a series of movable members for each scale of tone-emitting elements and means by which said members are moved under control of the control ducts to establish or break connection between the respective tone ducts and tone-emitting elements, and further including a locking element for each movable member and means under control of the tone-ducts for moving the locking elements into or out of holding engagement with the respective movable members.

7. In a mechanism of the class described, the combination with the two separate scales

of tone-emitting elements, a series of tone ducts common thereto and control ducts for the scales, respectively, of operative connections between the ducts and tone-emitting elements, said connections including tone-circuits for the scales of tone-emitting elements, each of said circuits having a member movable to make or break the circuit, means under control of the control ducts for operating said members, a locking element for each member and means under control of the tone-ducts for moving the locking elements into and out of holding relation with the respective movable members.

8. In a mechanism of the class described, the combination with the two separate scales of tone-emitting elements, a series of tone ducts common thereto and control ducts for the scales, respectively, of operative connections between the ducts and tone-emitting elements, said connections including a series of movable members for each scale of tone-emitting elements, respectively, one series of said members being normally in position in which the connection to the corresponding tone-emitting elements is established when the corresponding tone duct is open and the other series of said members being normally in position in which the connection to the corresponding tone-emitting elements is broken, means under control of one control duct, tending to move the last mentioned series of movable members to cause the corresponding tone-emitting elements to be operated when the respective tone ducts are opened, means under control of the other control duct tending to move the other series of movable members to break the connection to the corresponding series of tone-emitting elements, and locking elements under control of the tone ducts for resisting said tendencies as to the movable members corresponding to tone ducts which are open at the time either control duct is opened.

9. In a mechanism of the class described, the combination with the two separate scales of tone-emitting elements, a series of tone ducts common thereto and control ducts for the scales, respectively, of operative connections between the ducts and tone-emitting elements, said connections including tone circuits having a set of circuit making or breaking members for each scale of tone-emitting elements and an additional set of circuit making or breaking elements common to both scales, one of the first mentioned sets being normally in circuit making position and the other normally in circuit breaking position, means under control of one control duct, tending to move the last mentioned set of circuit making or breaking members into circuit making position, means under control of the other control duct, tending to move the other set of circuit making or breaking members into circuit breaking position.

position, means under control of the tone ducts for operating the additional set of circuit making or breaking members, a set of locking elements for each first-mentioned set 5 of circuit making or breaking members, and means under control of the tone ducts for operating the locking elements.

10. In a mechanism of the class described, the combination with the two separate scales 10 of tone-emitting elements, a series of tone ducts common thereto and control ducts for the scales, respectively, of operative connections between the ducts and tone-emitting elements, said connections including primary 15 and secondary operating pneumatics, means under control of the control ducts for controlling the relative pressures to which the primary operating pneumatics are subjected, connections between the primary operating 20 pneumatics and the secondary operating pneumatics for controlling the relative pressures to which the latter are subjected, having movable members operated by the primary operating pneumatics to make or 25 break the connections, locking elements, and means under control of the tone ducts for moving the locking elements into holding relation with the movable members.

11. In a record controlled musical instrument, tone-emitting elements, tone circuits and tone ducts; a series of pneumatically operable valves under control of said ducts, respectively, pneumatics controlled by said valves, respectively, and circuit making and 35 breaking members wholly controlled by said pneumatics, respectively, and included in the tone circuits.

12. In a record controlled musical instrument, a plurality of scales of tone-emitting 40 elements, tone circuits therefor, respectively, said circuits including a plurality of sets of circuit making and breaking members, operating pneumatics for said members, means whereby the operating pneumatics for one 45 scale are normally expanded and the operating pneumatics for the other scale are normally deflated, means controllable by the record for energizing the tone circuits, means controllable by the record for varying 50 the pressures to which the operating pneumatics are subjected and means controllable by the record for making the change in relative pressures to which the operating pneumatics, are subjected ineffective with respect to those circuit making and breaking 55 members which are in circuits completed at the time the change in pressure is brought about.

13. In a record controlled musical instrument, a plurality of scales of tone-emitting 60 elements; mechanism to cause any one or more of the tone-emitting elements of either scale to be operated alone, or any one or more corresponding or non-corresponding 65 elements of both scales to be operated

together, said mechanism comprising connections to the scales of tone-emitting elements, including a set of relatively movable members for each scale and record-controlled means common to said sets for causing the 70 sounding of tones through those connections whose relatively movable members are in operative relation with each other, a record-controlled means for each set of relatively movable members, tending to move the movable members of the respective sets into or out of operative relation with the corresponding members of the connections, locking means and connections through which the locking means are operated co-incidently 75 with the first-mentioned record controlled means to resist said tendency as to those movable members which correspond to any first-mentioned record-controlled means which is in operation at the time the second-mentioned record-controlled means comes into 80 operation.

14. In a record controlled musical instrument, a plurality of scales of tone-emitting elements; mechanism to cause any one or 90 more of the tone-emitting elements of either scale to be operated alone, or any one or more corresponding or non-corresponding elements of both scales to be operated together, said mechanism comprising electrical 95 connections to the tone-emitting elements including primary circuit making and breaking members common to both scales, and a set of secondary circuit making and breaking members for each scale, a record-controlled 100 operating means for each set of secondary circuit making and breaking members, locking means for the secondary circuit making and breaking members and connections through which the locking means are 105 controlled by the primary circuit making and breaking members.

15. In a record controlled musical instrument, a plurality of scales of tone-emitting elements; mechanism to cause any one or 110 more of the tone-emitting elements of either scale to be operated alone, or any one or more corresponding or non-corresponding elements of both scales to be operated together, said mechanism comprising electrical 115 connections to the tone-emitting elements including a set of circuit making and breaking members for each scale, a record-controlled means for controlling each set of circuit making and breaking members, a set of locking 120 members for each set of circuit making and breaking members, and record controlled means, including elements common to the two sets of circuit making and breaking members and the two sets of locking members and connections between said elements and members, for controlling the circuits which include the former and coincidentally operating the corresponding locking members.

16. In a record controlled musical instrument, a plurality of scales of tone-emitting elements; mechanism to cause any one or more of the tone-emitting elements of either scale to be operated alone, or any one or more corresponding or non-corresponding elements of both scales to be operated together, said mechanism comprising connections to the scales of tone-emitting elements, 5 including a set of relatively movable members for each scale and record-controlled means common to said sets for causing the sounding of tones through those connections whose relatively movable members are in operative relation with each other, a record-controlled means for each set of relatively movable members, tending to move the movable members of the respective sets into or out of operative relation with the corresponding members of the connections, a set 10 of locking pneumatics for each set of relatively movable members, each locking pneumatic having an element to engage the corresponding movable member of the connections to the tone-emitting elements, and connections through which the locking pneumatics are operated coincidently with the corresponding first-mentioned record controlled means to resist the tendency of the second mentioned record-controlled means to move those movable members which correspond to any first-mentioned record-controlled means which is in operation at the time the second-mentioned record-controlled 15 means comes into operation, the last named connections including a set of valves controlled by said first-mentioned record-controlled means and each common to corresponding pneumatics of both sets of locking pneumatics.
17. In a record-controlled musical instrument, a plurality of scales of tone-emitting elements; a series of tone-ducks common to said plurality of scales and mechanism to bring any one or more of the tone-emitting elements of either scale alone, or any one or more corresponding or non-corresponding elements of both scales together, into communication with their tone ducts, the said mechanism including chambers which are normally under suction, connections between the tone ducts and the tone-emitting elements, having a series of operating pneumatics in the respective chambers and movable members carried by said pneumatics, connections through which the operating pneumatics in one chamber are normally expanded and the operating pneumatics in the other chamber are normally collapsed, said connections including a record-controlled valve operable to change the pressure in the normally expanded set 20 of pneumatics to one tending to cause the same to collapse, and a second record controlled valve operable to change the pressure in the normally expanded set 25 of pneumatics to one tending to cause the same to collapse, a set of locking pneumatics for each set of operating pneumatics, said locking pneumatics having means to engage the corresponding movable members of the operating pneumatics and connections between the sets of locking pneumatics and tone ducts.
18. In a record-controlled musical instrument, a plurality of scales of tone-emitting elements and a series of tone-ducks common to both scales, of tone-connections between the tone-ducks and the scales of tone-emitting elements, the connections including sets of movable members respectively corresponding to the tone-emitting elements and means for moving said members into or out of operative relation with other members of the connections, including a set of operating pneumatics for the movable members corresponding to one scale of tone-emitting elements, a set of operating pneumatics for the movable members corresponding to the other scale of movable members, means through which one set of pneumatics are normally subjected to an internal pressure tending to expand the same, means through which the other set of pneumatics are normally subjected to an internal pressure tending normally to cause the same to collapse, and record controlled means for changing said internal pressures.
19. A mechanism substantially as set forth in claim 18 and wherein the respective sets of operating pneumatics are mounted in chambers which are under suction, the pressure of the air in one set of pneumatics being normally atmospheric and the pressure of the air in the other set of pneumatics being normally less than atmospheric.
20. In a record controlled musical instrument, a plurality of scales of tone emitting elements, tone circuits therefor, respectively, said circuits including a plurality of sets of circuit making and breaking members, operating pneumatics for said members, resilient means to move said members, means for producing a difference between the inside and outside of said pneumatics to collapse the same, overcome the resilient means and operate the circuit making and breaking means.
21. In a record controlled musical instrument, a plurality of scales of tone emitting elements, tone circuits therefor, circuit making or breaking means for one of said circuits, a chest having a suction chamber, a pneumatic within said space and connected to said circuit making or breaking means, means comprising suction connections for inflating and deflating said pneumatic to operate the circuit making or breaking means.
22. In a record controlled musical instrument, a plurality of scales of tone emitting

elements, tone circuits therefor, circuit making or breaking means for one of said circuits, a chest having a suction chamber, a pneumatic within said space and connected 5 to said circuit making or breaking means, means comprising suction connections for inflating and deflating said pneumatic to operate the circuit making or breaking means, and pneumatic locking members within said 10 suction chamber for locking said circuit making or breaking means.

23. In a mechanism of the class described, the combination with two sets of scales of tone emitting elements, a series of tone ducts 15 common to said scales, control ducts for said scales, operative connections between the ducts and tone-emitting elements, including tone circuits, control mechanism, circuit making and breaking means for said tone 20 circuits, a suction chamber, normally collapsed pneumatics corresponding to one of the scales and being within said suction

chamber and operating said making and breaking means, normally expanded pneumatics corresponding to the other scale and 25 being within the suction chamber, locking elements for the making and breaking means and means under control of the tone ducts for operating the locking elements.

24. In a record controlled musical instrument having a two scale tone emitting element, tone ducts and tone circuits for 30 said elements, common to the scales, two circuit making and breaking means in each of said tone circuits common to the two 35 scales, means for controlling the making and breaking means, two locking means for the controlled means, and connections to operate the two locking means to hold the making and breaking means in the position in 40 which they were when the tone duct was open, until the tone duct is closed.

In testimony whereof I affix my signature.
HEINRICH BOCKISCH.
